UNITED STATES PATENT OFFICE

WILLIAM L. TAYLOR, OF CINCINNATI, OHIO

MULTIPLEX BAG

Application filed July 22, 1927. Serial No. 207,675.

My invention relates to an improved method of making bags and more particularly to duplex bags in which a novel construction of the inner ply or liner blank and outer ply or cover blank form important parts of the finished bag. Reference is made to my copending application, Serial No. 199,540 filed June 17, 1927.

My invention is especially adapted for use in the manufacture of duplex or lined bags, usually employed for packing and shipping merchandise, such, for instance, as smoking and chewing tobacco, it being necessary that packages containing this class of goods be made, not only from air and moisture-proof material, but also after the bag has been filled with tobacco and closed, it has recently been desired to entirely surround or cover said filled bag with an additional cover of thin wax paper or a paper of similar moisture-proof construction. In order to efficiently apply and seal said additional cover of thin moisture-proof paper upon the filled and closed bag by the tobacco manufacturer's packing equipment, it is essential that the bag be of perfect form and that the "ears" at the bottom of the bag be of limber or flexible construction, whereas heretofore the flexibility of said "ears" was not an important factor, nor was the trueness in shape of the bag so particular. However, the flexibility of said "ears" and the correctness of shape of said bag are very essential features when it is desired to put said additional moisture-proof cover upon said filled and closed bag by the manufacturer's present packing equipment.

The primary object of the present invention is to provide an improved inner ply or liner blank, an improved outer ply or cover blank, and an improved method of making same, which entirely eliminates the objections and difficulties above referred to, and the practice of which improved method results in a better made or "squarer" shaped bag with a minimum number of cast-offs, due to the required exactness of the bags for applying said additional cover of thin moisture-proof paper by the tobacco manufacturer's packing equipment.

Further objects of my invention are to provide a multiplex bag, as above described and for the purposes intended, which is simple, efficient, inexpensive to manufacture, and the construction of which is highly desirable for use upon packing equipment where an additional cover of thin moisture-proof paper is applied to the bag after the latter has been filled, closed and sealed by said packing equipment.

Briefly and generally stated, the invention consists in cutting away a portion of the inner ply or liner blank (adjacent the portion of the cover blank forming the ears of the bag, previous to being superposed upon said cover blank and adhesively secured thereto) and cutting away a portion of the outer ply or cover blank at an angle to the central transverse fold, so that the excess quantity of paper heretofore folded within the "ears" (thereby making them stiff and non-flexible) is eliminated, thus making them limber or flexible and easily handled by the manufacturer's packing equipment.

My invention further consists in the construction, combination, location and arrangement of parts and in the bag as an article of manufacture, as herein set forth and claimed.

In the drawings:

Fig. 1 represents a longitudinal strip or web of paper, the longitudinal edges of which have a portion cut away at spaced intervals, as shown;

Fig. 2 represents two longitudinal superposed strips or webs of paper of different widths pasted together at intervals a short distance from their longitudinal edges and at certain points or spots in the center thereof, the liner or upper web of paper being cut away at its longitudinal edges at spaced intervals, as shown in Fig. 1, previous to being superposed upon the narrower web or cover ply of paper;

Fig. 3 is a similar view to Fig. 2, showing by dot and dash lines the parts cut away in forming the individual bag blanks and showing one of the bag blanks detached and discarded or waste parts cut away;

Fig. 4 is a plan view of the bag blank for a single bag clearly showing the cut-out por-

tion of the liner and cut away portion of the cover;

Fig. 5 is a plan view of the liner blank for a single bag; and

5 Fig. 6 is a plan view of the cover blank for a single bag.

Fig. 7 is a modified construction of the cut-out of the liner 1^a;

10 Fig. 8 is another modified construction of the cut-out in liner 1^a;

Fig. 9 is a side elevational view of a bag formed according to the blank shown in Fig. 4, part of which is broken away and shown by vertical section and the ears of which are 15 shown before being bent in close proximity with the bottom of the bag;

Fig. 10 is a similar view showing the ears folded against the bottom of the bag;

20 Fig. 11 is an edge view of the bag shown in Fig. 9;

Fig. 12 is an enlarged vertical section taken through one of the ears of the bag on a plane corresponding to line 12—12 of Fig. 11, the folded position of the ear being shown by 25 dotted lines;

Fig. 13 is an enlarged vertical section taken on a plane corresponding to line 13—13 of Fig. 11, looking in the direction of the arrows; and

30 Fig. 14 is an enlarged vertical section similar to Fig. 13 but of the old construction, showing the multiplicity of plies of paper within the ears.

The method of making the bag is substantially as follows:

A plurality of webs or plies of paper 1^a and 2^a, respectively, are drawn in registry with each other from rolls by any suitable means. The web 1^a, however, is provided 40 with cut-away portions 1^b previous to being superposed upon the ply of paper 2^a. Narrow layers of glue or paste 3 are applied near the respective longitudinal edges between the adjacent webs or plies of paper 1^a and 2^a on side 4 of the bag blank 5. Said layers of glue 45 preferably extend from end 6 to "scored" line 7. It has been found in practice, however, that by omitting a small portion of the glue stream at 8 over the "score" line 9, the top closure portion of the bag is more readily 50 handled by the manufacturer's packing equipment. The plies of paper are then pressed together upon said layers of paste whereby they are permanently attached to 55 together in accurate registry with each other, as shown in Fig. 2.

The important step of the operation consists in dieing out or cutting off the longitudinal strips 20 from side 4, which strips are 60 shown detached in Fig. 3. The edges of side 10 are then folded inwardly to form inturned 65 securing flaps 11.

A coat or layer of glue paste 11" is then applied to the exposed surface of each outer 65 flap 11, as shown in Fig. 3. The individual

bag blank 5 is then severed or cut off from the webs of paper 1^a and 2^a, respectively. The sides 4 and 10 of said bag blank are then folded transversely on central "score" line 12 and the longitudinal edges of side 4 of the bag are then pressed down upon the glued faces 11" of flaps 11 whereby the bag is completed and issued from the bag machine in a "flat" form.

To prevent the liner 1 from bulging or separating from the cover 2 at the top of the bag when the bag is opened by the manufacturer's packing equipment previous to filling with tobacco, I apply a spot or drop of glue 13 between said cover and liner, as 75 clearly shown in Figs. 2, 3 and 4, respectively.

The inside ply or liner is permanently fastened to the outer ply or cover by this method of construction to prevent shifting or withdrawal thereof, which is a decided 80 advantage, particularly on account of the easy and simple manner in which it is mechanically accomplished. The plies of paper 1^a and 2^a being glued together in registry with each other, after ply 1^a has been cut 90

away at 1^b, as shown in Fig. 1, said plies are held in absolute and accurate registry with each other during the subsequent operations, thereby preventing any shifting of the plies relative to each other, as is the case 95 where the plies are glued together after the dieing out operation. Two or more complete rolls of paper can be glued together, as shown in Fig. 2, on a separate machine before making it up into bags, ready for printing, and this can be done on a very simple combining and rewinding machine. In other words, the plies of paper can be unwound 100

from separate rolls and after dieing out the portion at 1^b of the liner, the plies of paper 105 may be glued together at the necessary points and then rewound upon a single roll for manufacture into bags on simple bag making machinery, such as is used for making bags of single ply material. In doing 110 this, all that is required is to mark or cut into the paper an identifying mark to show the registry point for the dieing out knives of the bag making machine. In this way, if desired, the cutting away of ply 1^a and the 115 gluing together of plies 1^a and 2^a, as shown in Fig. 2, could be done by one organization or factory and the dieing out and completing of the bag, as shown in Fig. 3, could be 120 done by another organization or factory, so that if the sheets or plies of paper are glued together the material can be handled as if it were a single piece of paper, instead of a plurality of sheets of paper. This is a 125 decided advantage in the construction of the bag since it enables the bag to be constructed more readily and economically by the use of simple, instead of complicated, machinery.

The inturned flaps of the inner and outer 130

plies 1^a and 2^a, respectively, being glued together, form a stronger and more substantial construction than otherwise.

The chief advantage of this invention is that the dieing out or cutting away of the liner 1^a at 1^b, previous to adhesively securing said ply 1^a upon ply 2^a eliminates any excess paper from being folded within the ears of the bag when formed ready for receiving its contents. A bag blank formed in this manner permits an additional covering of moisture-proof paper to be easily applied or put on after the bag has been formed, filled and closed by the manufacturer's packing machinery.

While I have set forth a particular construction and method, it will be understood that this is merely by way of illustration and the invention is capable of modification without material departure from its scope or spirit as defined in the claims, as for instance, as shown in Figs. 7 and 8, respectively, the inner ply or liner 1^a may be cut, as shown at 1^c or 1^d, which will also aid in producing a bag of the character described so that the "ears" of said bag will not be held in open position by their stiffness but will readily assume a position in close proximity with the bottom of the bag when said bag is in the open position ready for receiving its contents.

What I claim as new and desire to secure by Letters Patent is:

1. A multiplex bag having outwardly extending ears and comprising a cover and liner, the liner being entirely removed or cut out in that portion of the bag which forms the ears to permit said ears to be perfectly and compactly folded against the bottom of the bag.

2. A multiplex bag having outwardly extending ears and comprising a cover and liner, the liner being entirely removed or cut out only in that portion of the bag which is folded to form the ears so that said ears may be easily and compactly folded against the bottom of the bag.

WILLIAM L. TAYLOR.
